UNITED STATES PATENT OFFICE.

DONALD BARNS MORISON, OF HARTLEPOOL, ENGLAND.

EVAPORATOR.

Application filed March 28, 1923. Serial No. 628,339.

To all whom it may concern:

Be it known that I, DONALD BARNS MORISON, of Hartlepool, in the county of Durham, England, have invented certain new and useful Improvements in Evaporators, of which the following is a specification.

This invention relates to apparatus for evaporating liquids such for example, as are employed for the production of fresh water by the evaporation of salt or impure water for use as boiler feed water.

The object of this invention is to improve the efficiency and general convenience of the apparatus as a whole, particularly with regard to promoting upward circulation throughout the heating coil chamber, drying the generated steam and facilitating the construction—attachment and removal of the steam drying and steam generating devices.

I have found that the efficiency of the steam generating surfaces is increased when the circulation throughout the cross section of the heating zone—comprising the heating coil chamber—is uniform and upward and that given upward and uniform circulation the turbulence on the surface area of the boiling water is evenly distributed, thereby promoting a greater generation of steam without excessive wetness. According to my invention the drainage water from the separating devices, the feed water supply, together with water from the steam bubble zone, pass downwardly through one or more passages and together form the downwardly circulating supply which is distributed below the heating surfaces and which passes uniformly upwardly throughout the heating zone. That is to say the water is in continuous circulation upwardly throughout the heating zone, and from the bubble zone downwardly through the independent passage or passages for admission and distribution below the heating zone.

Above the heating surface, a perforated plate is fixed and provided with a gutter-way or channel through which the separated water is led to a passage terminating below the heating surface. Towards the top of the evaporator the steam is caused to flow upwardly against a diaphragm by which it is deflected downwardly into a water separating chamber provided with pipes or other devices through which the separated water passes to a depositing plate and is led as before to below the heating

surface. The heating surfaces are usually horizontally disposed tubular coils in pairs and are, according to this invention, attached to a ported flange common to the inlet and outlet ends of the coil which is held in position by one or more bolts operated from outside the evaporator, the steam supply and exhaust chambers being embodied in a casing preferably removable.

In the accompanying drawings I have illustrated an evaporator constructed in accordance with the invention. In these drawings Fig. 1 is an elevational view, Fig. 2 a vertical section on the line 2—2 of Fig. 1, Fig. 3 a transverse section on the line 3—3 of Fig. 2, Fig. 4 is a plan view partly in section illustrating a coil and its means of attachment which in the example shown is removable, Fig. 5 is an elevational view thereof partly in section on the line 5—5 of Fig. 6, Fig. 6 is a view looking in the direction of the arrow A and Fig. 7 is a similar view looking in the direction of the arrow B. Fig. 8 is a vertical sectional view of one form of liquid collecting device, Fig. 9 is a transverse section thereof on line 9—9 of Fig. 8, Figs. 10 and 11 are similar views of a modified form of such device, the section of Fig. 11 being taken on the line 11—11 of Fig. 10.

Referring to these drawings the numeral 1 designates the evaporator shell within the lower part of which the steam coils 2 are located, the shell being provided with an opening 3 closed by a door 4, through which the coils can be withdrawn for inspection and cleaning as will hereafter appear. The coils are arranged horizontally and superimposed one upon the other and the ends of each coil are brought together and brazed or otherwise secured to a fitment 5 which makes junction with a removable steam and exhaust receiver or chest 6, a single bolt 7 adapted to pass through this removable chest serving in conjunction with the nut 8 to hold the coil securely in position. Thus each complete coil is held in position by one bolt which is accessible from outside the evaporator shell and it will be seen that by slackening back the nut 8 and unscrewing the bolt 7 each coil as a whole can be removed through the opening 3. By reason of the removability of the steam and exhaust receiver or chest 6 the coils can be connected up to this chest and tested prior to their final assembly within the evaporator shell.

The door 4 closing the opening 3 is provided with an inlet chamber 9 to which an inlet feed nozzle 10 leads and the liquid to be evaporated is introduced through this nozzle 10, openings 11 in the bottom of the chamber 9 permitting the liquid to flow to the base of the evaporator which is provided with the usual blow down opening 13. Immediately above the coils and within or close to the bubble zone a perforated baffle or partition 14 is provided and unevaporated liquid deposited on the upper surface thereof can pass from this plate downwardly into the inlet chamber 9 where it mixes with the incoming liquid and passes downwardly back to the base of the evaporator below the coils. The upward passage of vapour through the perforations is sufficient to prevent the greater portion of the separated liquid falling on the plate from passing through the perforations, so that it runs off and is discharged over its edge down the passage 9. Near the top of the steam dome of the evaporator I provide a water separating device or steam drier and this separating device is preferably bodily removable through an opening 14 closed by a door or panel 15.

This separating device comprises a central pipe 16 upstanding from a collecting tray or channel 18 and passes through a perforated plate 17 which may cover the collecting tray. Over the top of this central pipe a baffle 19 is arranged and collecting rings or channels 20 depend from this baffle, these collecting rings draining by means of pipes 21 passing through the current of steam from which the liquid has been separated into the collecting tray 18 so that any condensed vapour is trapped and finally drains off the tray 18 through an opening 22 in its flange into a vertical channel 23 in the wall of the evaporator shell and thence passes back to the base of the evaporator beneath the coils. It will be understood that the number of the collecting rings 20 depending from the baffle 19 may vary as desired. In Figs. 1, 8 and 9 only one is shown whereas in Figs. 10 and 11 two are shown and it will be readily understood that a series may be provided if necessary or desirable. A vapour outlet 24 is provided and steam is admitted to the coils in the usual way through an outlet 25. It will be seen that by reason of the foregoing construction and arrangement the liquid separated from the generated vapour together with liquid from the ebullition zone are led back and distributed beneath the heating coils so that uniform upward circulation through the heating zone is promoted. All the liquid separated from the vapour passes to below the heating coils 2 by the passages

23 and 9 so that such returned liquid will not interfere in any way with the upward circulation in the evaporator.

What I claim and desire to secure by Letters Patent is:—

1. An evaporator in which liquid is separated from the vapour, comprising heating coils, a removable door through which the heating coils may be removed, and two separators each having a downwardly extending liquid discharge passage, one of the separators being secured in the upper portion of the vapour space of the evaporator while the other is secured in the ebullition zone in the lower portion of the vapour space of the evaporator, the discharge passage from the upper separator being formed integral with the walls of the evaporator and exterior to the heating coil chamber while the discharge passage from the lower separator is formed on the inner side of the removable door.

2. An evaporator in which liquid is separated from the vapour, comprising heating coils, a receiver, a removable door in the walls of the evaporator, a separator secured in the upper portion of the vapour space near the outlet thereof, a liquid discharge passage in walls of the evaporator and integral therewith opening at one end into the upper portion of the evaporator and at the other into the space below the coils, a second separator arranged immediately above the coils, a second liquid discharge passage on the inner side of the door, and open at its lower end into the space below the coils, the coils being supported by and leading into the receiver, the first liquid discharge passage receiving at its upper end liquid from the separator, while the second liquid discharge passage receives at its upper end liquid from the lower separator.

3. An evaporator in which liquid is separated from the vapor comprising heating coils, a removable door through which the heating coils may be removed, two separators each having a downwardly extending liquid discharge passage, one of the separators being secured in the upper portion of the vapor space of the evaporator, and having its liquid discharge passage integral with the walls of the evaporator and exterior to said heating coil chamber and discharging liquid below the ebullition zone of the evaporator, the other separator being secured in the ebullition zone in the lower portion of the vapor space of the evaporator, its discharge passage being formed on the inner side of the removable door and discharging its liquid below the coils.

In testimony whereof, I affix my signature.

DONALD BARNS MORISON.
